United States Patent Office

Des. 174,648
Patented May 3, 1955

174,648

EARRING OR THE LIKE

Elbert C. Mathias, Albuquerque, N. Mex.

Application August 5, 1954, Serial No. 31,748

Term of patent 7 years

(Cl. D45—9)

To all whom it may concern:

Be it known that I, Elbert C. Mathias, a citizen of the United States of America and a resident of Albuquerque, State of New Mexico, have invented a new, original, and ornamental Design for an Earring or the like, of which the following is a specification, reference being had to the accompanying drawing, forming a part hereof.

I claim:

The ornamental design for an earring or the like, as shown.
